United States Patent Office.

WILLIAM C. HUTCHINGS, OF HARTFORD, CONNECTICUT.

Design No. 3,374, dated February 16, 1869.

DESIGN FOR A TRADE-MARK

The Schedule referred to in these Letters Patent and making part of the same.

To all whom it may concern:

Be it known that I, WILLIAM C. HUTCHINGS, of Hartford, in the county of Hartford, and State of Connecticut, have originated a new Design for a Trade-Mark, of which the following is a full, clear, and exact description, reference being had to the accompanying drawing, making part of this specification.

My design consists in a circular central field, containing a perspective representation of a R. Hoe & Co.'s printing-press, with the words "Trade-Mark" upon the fly.

From the central field, radial rays diverge, in the form of a sixteen-pointed star.

Across these rays, around the top, and parallel to the circumference of the central field, are the words,

"Hartford Press," and around the bottom, across the rays, likewise parallel to the circumference of the central field, are the words, "Wm. C. Hutchings & Co. The above-named words are composed of black letters shaded for a light coming from the centre, and form a circle around the central figure.

Claim.

What I claim as my invention, and desire to secure by Letters Patent, is—

The design for a trade-mark herein set forth.

WM. C. HUTCHINGS.
